UNITED STATES PATENT OFFICE.

WILLIAM HENRY SAUVAGE, OF NEW YORK, N. Y., ASSIGNOR, BY MESNE ASSIGNMENTS, TO ATLAS SLACK ADJUSTER COMPANY, OF NEW YORK, N. Y., A CORPORATION OF NEW YORK.

SLACK-ADJUSTER.

No. 867,677.

Specification of Letters Patent.

Patented Oct. 8, 1907.

Application filed September 1, 1906, Serial No. 332,890. Renewed June 21, 1907. Serial No. 380,089.

To all whom it may concern:

Be it known that I, WILLIAM HENRY SAUVAGE, a citizen of the United States of America, and a resident of the borough of Manhattan, city, county, and State 5 of New York, have invented certain new and useful Improvements in Slack-Adjusters, of which the following is a specification.

My invention relates to railway brakes, and comprises improved apparatus for automatically taking 10 up the slack in power operated brakes so that the amount of piston travel in the power cylinder will remain substantially constant as the brake shoes wear down or other parts of the brake rigging yield.

More specifically my invention in many of its 15 details comprises an improvement upon the construction illustrated and described in my previous application, Serial No. 298,191, filed January 27, 1906, allowed May 19, 1906.

The best form of apparatus embodying my invention at present known to me is illustrated in the accompanying two sheets of drawings, in which:

Figure 1 is a side elevation of portions of a car truck with my invention attached thereto. Fig. 2 is an enlarged plan view of the take-up and holding mechanism. Fig. 3 is a side elevation of the same, and Fig. 4 is a detail of one of the clutch dogs.

Throughout the drawings, like reference figures indicate like parts.

1 is a block attached to a draft timber 2, or other 30 convenient part of the car body.

3 is a bolster upon which the car body rests, and 4 a truck bolster connected to it by a king pin and center plate 5.

6, 6, represent car wheels, and 7, 7, brake shoes 35 applied thereto. These brake shoes are carried by brake beams 8, 8. The usual "live" lever 9 and "dead" lever 10 are pivoted to the brake beams, and have their lower ends connected by the bottom rod 11. The top rod 12 is connected to the upper end of 40 the "live" lever in the manner now in use in standard brake rigging.

13 is a bolt having preferably a square head 14, beveled off at one side 37, which bolt is used to fasten the main frame 20 to the block 1, as shown in Fig. 2. This 45 main frame is preferably formed of a strip of iron or steel, having short bent-up ends 21, 21, through which are punched or bored holes 23, 23. A second shorter frame 17, I call the take-up frame. Its bent-up ends 15, 15, are punched or bored to form holes 16, 16, 50 which will be in line with the holes 23, 23, when the parts are assembled, as shown in Fig. 2.

The take-up rod 24 passes through the holes in the ends of the frames 17 and 20, and on this rod are mounted two friction clutch dogs. These two dogs are of 55 exactly similar construction, but the holding clutch

dog 26 has its longer end 18 inmost, and bearing against the head 14 of the bolt 13, while the take-up clutch dog 31 has its shorter end 19 inmost so as to permit it to fit into the take-up frame 17. Each of these dogs has a hole 28 punched or bored in it, as shown in Fig. 60 4, which is about 1/32 of an inch larger in diameter than the take-up rod 24.

29 is a short spiral spring, preferably mounted on the take-up rod and compressed between the holding clutch dog 26 and one end 21, of the main frame. 33 65 is a similar spring also preferably mounted on the take-up rod and compressed between the take-up clutch dog 31 and one end 15, of the take-up frame.

27 is a reach rod having one end 32 bent at right angles and inserted between one end of the take-up 70 frame 17 and the inner end of the take-up dog 31, while its other end 30 loosely encircles the top rod 12 at a fixed distance from the point of connection to the "live" lever, or from the shoulder of the fork 35 on the end of the top rod, when the brakes are released. 75

36 is a strong spiral spring, preferably encircling the take-up rod and arranged with one end against the end of the holding frame and the other against the take-up frame normally forcing the latter up against the bolt head 14, or some other suitable fixed stop. 80

The take-up rod 24 has a loop or eye 22 formed in one end with which the clevis 25, pivoted to the upper end of the "dead" lever, is connected. The other end of the take-up rod has a cotter pin 34, or other suitable stop to prevent its being pulled through the 85 holding frame.

The operation of my invention is as follows: The parts being assembled, as shown in Fig. 1, 2 and 3, of the drawings, it is evident that any application of the brakes which causes the "live" lever 9 to travel to 90 the left (looking at Fig. 1) a distance greater than the space between the looped end of the reach rod 27, and the shoulder of the fork on the end of the top rod, will pull said reach rod to the left and the take-up frame 17, with it, compressing the take-up spring 36. On 95 releasing the brakes, the spring 36 will expand and force the take-up frame 17 to the right until its motion is terminated by the bolt head 14. During this return travel, the take-up dog 31 bearing against the bent end 32 of the reach rod as a fulcrum and controlled by the 100 spring 33, will clutch the take-up rod 24 and pull the same to the right a distance equal to the extent of movement of the take-up frame. The take-up rod will be held in this adjusted position at subsequent applications of the brake by means of the holding dog 26, 105 which permits motion of the take-up rod toward the right, but prevents motion toward the left.

Among the advantages of my invention may be mentioned the cheapness and ease of manufacture, all the parts being made out of bar iron or steel which can be 110

purchased in the market, no patterns or castings being required; and the interchangeability of parts, the two dogs being duplicates and the two springs controlling them being also interchangeable. An important feature of advantage is the construction by which the entire pull of the take-up rod when the brakes are applied is transmitted directly through the clutch dog 26 to the bolt 13, which is the means of attaching the whole apparatus to the car body. No strain of any consequence is transmitted through any of the other parts of the apparatus. The action of the clutch dogs upon the take-up rod is not affected by ice or rust or dirt, the clutches automatically cleaning the rod during the movement of the same through them. The operative connection by means of the bent end 32 of the reach rod 27 serves as a safety device in case of excessive movement of the "live" lever. In such case the take-up spring 36 might be compressed to a point beyond which it would not yield further and something must give way. The light reach rod will bend under such circumstances and its end 32 will be pulled out of engagement with the take-up frame or the loop upon its other end will open and no damage will be done to the other and more costly parts of the apparatus. Repairs can be made by simply bending the reach rod back into shape and replacing it. The take-up spring 36 pressing against the take-up frame on a line at one side of the line of resistance of the bolt head 14, which bears on the other side of the frame, tends to cant said frame and cause it to exert a wedging action on the take-up rod 24, preventing the same from jarring or creeping toward the right under the jolting action of the car. One face of the bolt head being beveled off, as shown at 37 in Fig. 2, tends to increase this wedging action. In order to let out the apparatus, it is only necessary to pull the two clutch dogs toward the right, when the take-up rod can be easily shoved through the frame toward the left.

It is evident that various changes could be made in the details of construction illustrated and described without departing from the spirit and scope of my invention so long as the general principle of construction and operation above described is preserved.

The bolt 13 serving as the sole means of attachment of the holding frame 20 to the car body or other support, it is evident that the whole apparatus may swivel slightly about said bolt in order to permit it to accommodate itself to any irregularities of movement of the dead lever 10, and still cause the pull of said dead lever to be transmitted in line with the take-up rod 24.

Having, therefore, described my invention, I claim:

1. A take-up and holding mechanism for automatic slack adjusters comprising in combination, a holding frame, a fulcrum projection rigidly located with reference to said frame, a take-up frame movable within said holding frame, a rod passing through both said frames, a take-up clutch dog mounted on said rod within the take-up frame, a holding clutch dog mounted on said rod and having one end pressing against the fulcrum projection and a spring normally tending to hold the take-up frame at a fixed position in the holding frame.

2. A take-up and holding mechanism for automatic slack adjusters comprising in combination, a holding frame, a fulcrum projection rigidly located with reference to said frame and forming part of the means for attaching the holding frame to its support, a take-up frame movable within said holding frame, a rod passing through both

said frames, a take-up clutch dog mounted on said rod within the take-up frame, a holding clutch dog mounted on said rod and having one end pressing against the fulcrum projection and a spring normally tending to hold the take-up frame at a fixed position in the holding frame. 70

3. A take-up and holding mechanism for automatic slack adjusters comprising in combination, a holding frame, a fulcrum projection rigidly located with reference to said frame and forming part of the means for attaching the holding frame to its support, a take-up frame movable within said holding frame, a rod passing through both said frames, a take-up clutch dog mounted on said rod within the take-up frame, a holding clutch dog mounted on said rod and having one end pressing against the fulcrum projection and a spring normally tending to hold the take-up frame at a fixed position in the holding frame pressed against the other side of the fulcrum projection for the holding dog. 80

4. A take-up and holding mechanism for automatic slack adjusters comprising in combination, a holding frame composed of a body portion with two ends bent up and perforated, a bolt passing through said body portion near one end and having its head on the inside of the frame, a take-up frame movable within said holding frame and having perforations in line with those in the ends of the holding frame, a rod passing through all of said perforations, a take-up clutch dog mounted on said rod within the take-up frame, a holding clutch dog mounted on said rod and having one end pressing against the above described bolt head and a spring mounted on the rod with one end against the end of the holding frame and normally forcing the take-up frame against the other side of the bolt head. 90

5. A take-up and holding mechanism for automatic slack adjusters comprising in combination, a holding frame composed of a body portion with two ends bent up and perforated, a bolt passing through said body portion near one end and having its head on the inside of the frame, a take-up frame movable within said holding frame and having perforations in line with those in the ends of the holding frame, a rod passing through all of said perforations, a take-up clutch dog mounted on said rod within the take-up frame, a holding clutch dog mounted on said rod and having one end pressing against the above described bolt head and a spring mounted on the rod with one end against the end of the holding frame and normally forcing the take-up frame against the other side of the bolt head, together with two other springs mounted on the rod and tending to force the clutch dogs into action. 100

6. The combination in a friction clutch of a frame composed of a middle portion and two bent end portions provided with perforations in line one with another, a rod passing through said perforations, a loose clutch dog having a perforation through which the rod also passes, a fulcrum projection rigidly located with reference to the frame and against which one end of the dog bears, and a spiral spring surrounding the rod, and compressed between one bent end portion of the frame, and the side of the dog opposite to the fulcrum. 105

7. The combination in a friction clutch of a frame composed of a middle portion and two bent end portions provided with perforations in line one with another, a rod passing through said perforations, a loose clutch dog having a perforation through which the rod also passes, a fulcrum projection rigidly located with reference to the frame and against which one end of the dog bears, and a spiral spring surrounding the rod, and compressed between one bent end portion of the frame, and the side of the dog opposite to the fulcrum, together with a take-up frame composed of a shorter middle portion and two bent end portions provided with perforations through which the rod also passes, a second loose clutch dog within said take-up frame and having a perforation through which the rod passes, a spring confined between said second clutch dog and one end of the take-up frame, and yielding means for holding the take-up frame against the before mentioned fulcrum projection. 110

8. A take-up and holding mechanism for automatic slack adjusters comprising in combination, a holding frame having bent up perforated end portions, a shorter take-up frame within the holding frame having bent up

- end portions perforated in line with the perforations in the ends of the holding frame, a take-up rod passing through all said perforations, a holding dog consisting of a piece of metal perforated nearer to one end than to the other mounted on the rod in the holding frame, with its longer end inmost, and a second take-up dog composed of a similar piece of metal mounted on the rod within the take-up frame with its shorter end inmost.
9. In a take-up and holding device for automatic slack adjusters, the combination of a take-up rod, a perforated clutch dog through which the rod passes, mechanism affording a fulcrum for one end of said dog, and a spring normally holding said dog in clutching position.
10. In an automatic slack adjuster for railway brakes, the combination with a take-up rod and holding device therefor, of a take-up frame, a perforated friction dog mounted on said rod in said take-up frame, and a reach rod for moving said take-up frame, the bent end of the reach rod passing through the take-up frame and serving 20 as a fulcrum for the clutch dog.
11. In an automatic slack adjuster for railway brakes the combination with the standard brake rigging comprising a "live" lever, a "dead" lever, and top rod connected to said "live" lever, of a take-up rod connected to the "dead" lever, a holding device therefor, a take-up device, and a reach rod connected at one end to the take-up device and having its other end loosely encircling the top rod.
12. A take-up and holding mechanism for automatic slack adjusters, comprising in combination a holding frame, a take-up rod sliding in said frame, a gripping mechanism for holding said rod in different positions of adjustment, and means for holding said gripping mechanism in the holding frame which also serve to fasten the holding frame to its support.
13. A take-up and holding mechanism for automatic slack adjusters, comprising in combination a holding frame, a take-up rod sliding in said frame, a gripping mechanism for holding said rod in different positions of adjustment and a device for holding said gripping mechanism in the holding frame which said means constitute 40 the sole means for connecting the holding frame to its support.
14. A take-up and holding mechanism for automatic brake slack adjusters which comprises in combination a holding frame, a take-up rod sliding in said holding frame, 45 a perforated friction clutch dog mounted on said rod, and a bolt passing through said frame and adapted to serve as its means of attachment to its support, the head of said bolt also serving as a fulcrum for the clutch dog.
15. A take-up and holding mechanism for automatic 50 brake slack adjusters which comprises in combination a holding frame, a take-up rod sliding in said holding frame, a perforated friction clutch dog mounted on said rod, and a swiveling bolt passing through said frame and adapted to serve as its sole means of attachment to its support, 55 the head of said bolt also serving as a fulcrum for the clutch dog.
16. In a take-up and holding device for automatic slack adjusters, the combination of a take-up rod, a perforated clutch dog through which the rod passes, mechanism 60 affording a fulcrum for one end of the dog, and means for normally holding said dog in clutching position.

Signed at New York, N. Y. this 31st day of August, 1906.

WILLIAM HENRY SAUVAGE.
